UNITED STATES PATENT OFFICE.

MORRES SEIGER, OF NEW YORK, N. Y., ASSIGNOR TO MORRES SEIGER AND SIMON SEIGER, DOING BUSINESS UNDER THE FIRM NAME OF M. SEIGER & SON, OF NEW YORK, N. Y.

DESIGN FOR A WATCHCASE OR SIMILAR ARTICLE OF MANUFACTURE.

Application filed September 9, 1922. Serial No. 3,662. Term of patent 14 years.

To all whom it may concern:

Be it known that I, MORRES SEIGER, a citizen of the United States, residing at New York, county of New York, State of New York, have invented a new, original, and ornamental Design for a Watchcase or Similar Article of Manufacture, of which the following is a specification, reference being had to the accompanying drawing, which forms a part thereof.

Fig. 1 is a front elevation of a watch case showing my new design.

Fig. 2 is an edge elevation of the watch case shown in Fig. 1.

I claim:

The ornamental design for a watch case or similar article of manufacture substantially as shown.

MORRES SEIGER.
